CLAIM

We claim the ornamental design for a three storage bin assembly for refrigerated appliance, substantially as shown and described.

DESCRIPTION

FIG. 1 is a perspective view of a three storage bin assembly for refrigerated appliance, showing our new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is another perspective view thereof, shown in a first alternate configuration;

FIG. 10 is another perspective view thereof, shown in a second alternate configuration; and,

FIG. 11 is another perspective view thereof, shown in a third alternate configuration.

The dot-dash broken lines immediately adjacent shaded areas represent the bounds of the claimed design while all other broken lines are included for the purpose of illustrating the unclaimed portions of the article; the broken lines form no part of the claimed design.
